UNITED STATES PATENT OFFICE

DUGALD S. PATERSON AND GUSTAV B. PETSCHE, OF CLEVELAND, OHIO, ASSIGNEES TO
THE NATIONAL ACME COMPANY, OF CLEVELAND, OHIO, A CORPORATION OF OHIO

SCREEN SEPARATING MEANS

Application filed April 6, 1928. Serial No. 267,821.

This invention relates to screen separating means, commercially called electric screens, particularly adapted for the separation of fluids and semi-fluids, an object of the invention being to provide an improved screen separating means which will have a combined vibrating, oscillating and rotating motion and therefore substantially a universal movement so that every square inch surface of the wire mesh is agitated thereby preventing the formation of eddies either in the center of the screen or around the periphery thereof.

A further object of the invention is the provision of an improved screen separating means which can be readily attached to receptacles of different diameters or of different shapes and in which screen separating pans of different sizes or of a different wire mesh can be readily interchanged, and which will be simple in construction, efficient in operation, and extremely flexible for mounting on varying shapes and sizes of tanks as well as for the substitution of pans of different mesh or of different size.

In the drawings accompanying and forming part of this specification, Figure 1 is a top view of this improved screen separating means; Fig. 2 is a side view thereof; Fig. 3 is a detail sectional view of the operating means for the screen pan; Fig. 4 is a front view of the screen pan with a part of the bearings and a part of the receptacle to which it is attached shown in section; Fig. 5 is a top partial sectional view of Fig. 4; Fig. 6 is a detail sectional view of the anti-friction bearings for the screen separating pan, and Fig. 7 is a detail sectional view of the means for clamping the screen pad to a receptacle.

Similar characters of reference indicate corresponding parts in the several views.

Before explaining in detail the present improvement and mode of operation thereof, we desire to have it understood that the invention is not limited to the details of construction and arrangement of parts which are illustrated in the accompanying drawings, since the invention is capable of other embodiments, and that the phraseology which

we employ is for the purpose of description and not of limitation.

This improved screen separating means in the preferred form thereof shown comprises a screen pan 2 consisting of a rim 3 curved inwardly at its top, as at 4, to direct the fluid toward the interior of the pan and prevent splashing thereover. The bottom of this pan is formed of a suitable wire mesh or wire cloth 5. Encircling the pan is a two-part clamping band 6 adjustable to fit different sizes of pans, the two parts being hinged as at 7. This band engages the pan under a flanged rim 7' riveted to the pan insuring the proper positioning of the pan.

In the form shown one part of this clamping band has one end provided with a pair of lugs or ears 8 and 9 for the reception of a threaded rod 10 forming the other part of the band, the opposite end of which is hinged to the band part 6. This rod is curved to conform to the shape of the pan and the end of this rod has a thumb nut 11 and a check nut 12 whereby the clamping device may be adjusted to fit varying sizes of pans.

At the hinged connection of the band is located a cam lever clamping device 13 for insuring a tight fitting of the band to the pan, and for this purpose the curved rod 10 is provided at its end with a curved member or cam arm 14 to which is pivoted a hand lever 15, the inner end of which is pivotally connected between a pair of lugs or ears 16 on the other member of the band so that by throwing the lever in one direction as in a dead center position or away from the pan, the clamping band will be securely fastened or released from the pan so that the pan can be readily removed and replaced. This clamping band is connected with a rectangular supporting frame 17 by a pair of anti-friction bearings 18, one at each side and diametrically opposed and for this purpose the clamping ring is provided with a pair of bearing members 19 rigidly secured thereto and recessed to receive balls 21. These bearing members 19 cooperate with a pair of bearing members 20 rigidly secured to the rectangular frame 17 and between the co-operating bearing means the anti-friction bearings

or balls 21 are located. The rectangular frame 17 is provided with a plurality, shown as four in number, of swiveled sliding clamps 22 for attachment to the receptacle. Each of these clamps 22 comprises a U-shaped or forked member 23 carrying a thumb-screw or bolt 24 for clamping it to the rim of the receptacle or tank. This forked member is provided with a spindle or bolt 25 carrying a pair of clamping members 26 for the reception of the rectangular frame 17, and the top of the bolt 25 is provided with a thumb nut 27 whereby the clamping members 26 can be tightly clamped to the rectangular frame. 5

10 By this sliding and swiveled clamping means it will be observed that the screen separating pan may be readily attached to the top of a tank of varying sizes and shapes. 15

The ends of the rectangular frame 17 are 20 connected by a bolt or reinforcing rod 28. For imparting vibratory movement to the separating pan the clamping band 6 is provided with a rearwardly extending crank arm 29 having a bore 30 fitting an eccentrically formed hub 31 of a bevel gear 32 loosely mounted upon a spindle 33 carried by a motor base or plate 34. This gear 32 is in mesh with a bevel gear 35 carried by the shaft of a suitable small motor 36 mounted 25 on the motor base or plate 34, and this motor base or plate is rigidly secured to the rectangular frame 17 whereby the whole mechanism can be readily and quickly detached and replaced as a unit. The bevel gear 32 is counter-weighted to neutralize its vibration and this counter-balancing is obtained in the present instance by forming the gear with recesses or openings 37 and then filling in one of these recesses with lead as at 38. 30

35 From the foregoing it will be observed that the screen separating pan is supported by only two anti-friction bearings oppositely located and that by reason of the eccentric connection between the bevel gear 32 and the crank arm 29, the pan is given a forward and backward movement and a sidewise movement in a rotary path so that there is substantially a universal movement of the pan with the result that every square inch of 40 surface of the wire mesh is agitated, thus preventing the formation of eddies either in the center of the screen or around the periphery thereof. It will also be seen that the pan may be readily supported on tanks, not 45 only of different sizes or diameters, but on round or square tanks, since the swiveled clamps secured to the rectangular frame may be slid along the same to any desired position and by means of the adjustable clamping band various sizes of pans may be interchanged and tightly clamped in position for 50 shiftable movement by the motor driven gearing, so that the construction of this separating means is simple in design, efficient 55 in operation and flexible for mounting it on

tanks of varying shapes and sizes and for the interchanging of screen pans of different sizes or having different wire mesh.

In practice, the driving mechanism may be suitably enclosed by a cover or casing 39, thus providing a very simple, easily handled screen separating means. 70

It is to be understood that by describing in detail herein any particular form, structure or arrangement, it is not intended to limit the invention beyond the terms of the several claims or the requirements of the prior art. 75

Having thus explained the nature of our said invention and described a way of constructing and using the same, although without attempting to set forth all of the forms in which it may be made, or all of the modes of its use, we claim: 80

1. In a screen separating means, the combination of a pan, a clamping band therefor adjustable to receive varying sizes of pans, cam operated means for locking the clamping band to the pan, a supporting frame, swivelled and sliding clamping devices for connecting the frame with tanks of different sizes and shapes, a pair of anti-friction bearings between the frame and the clamping band, and means for shifting the pan relatively to the frame. 95

2. In a screen separating means, the combination of a pan, a clamping band therefor adjustable to receive varying sizes of pans, cam operated means for locking the clamping band to the pan, a supporting frame, swivelled and sliding clamping devices for connecting the frame with tanks of different sizes and shapes, a pair of anti-friction bearings between the frame and the clamping band, and means eccentrically connected with the band for shifting the pan relatively to the frame. 100

3. In a screen separating means, the combination of a pan, a clamping band therefor adjustable to receive varying sizes of pans, cam operated means for locking the clamping band to the pan, a supporting frame, swivelled and sliding clamping devices for connecting the frame with tanks of different sizes and shapes, a pair of anti-friction bearings between the frame and the clamping band, and means for shifting the pan in a rotary path in a horizontal plane relatively to the frame. 110

4. In a screen separating means, the combination of a supporting frame, a plurality of slideable and swiveled clamps for connecting the frame to tanks of varying sizes and shapes, a separating pan, a lockable clamping band therefor, anti-friction bearings connecting the clamping band with the frame, and means for shifting the pan. 120

5. In a screen separating means, the combination of a supporting frame, a plurality of slideable and swiveled clamps for connect- 125

5 ing the frame to tanks of varying sizes and shapes, a separating pan, a lockable clamping band therefor, anti-friction bearings connecting the clamping band with the frame, and means for shifting the pan.

6. In a screen separating means, the combination of a supporting frame, a plurality of slidable and swiveled clamps for connecting the frame to tanks of varying sizes and 10 shapes, a separating pan, a lockable clamping band therefor, anti-friction bearings connecting the clamping band with the frame, and means for shifting the pan in a rotary path in a horizontal plane.

15 7. In a screen separating means, the combination of a bracket, a supporting frame carried thereby and provided with swiveled and shiftable clamps for attaching the frame to various sizes and shapes of tanks, an adjustable clamping band pivotally supported by said frame at diametrically opposed points and adjustable to receive different sizes of 20 screen pans, and means carried by the bracket and connected with the clamping band for 25 vibrating the same and thereby the pan in a horizontal plane in a rotary path.

8. In a screen separating means, the combination of a supporting frame comprising a pair of connected parallel bars, swiveled 30 clamping means carried by said bars to connect the frame to various sizes and shapes of tanks, a circular clamping band pivotally supported at a pair of opposed points on the supporting frame and adjustable to receive 35 different sizes of circular pans, and means connected with one end of the supporting frame exteriorly thereof for vibrating said clamping band and thereby the pan in a rotary path in a horizontal plane.

40 9. In a screen separating means, the combination of screen supporting means adjustable to interchangeably support screen pans of different sizes, means adjustable to support the pan supporting means upon different 45 sizes and shapes of receptacles, connecting means between said two supporting means whereby the pan may be vibrated with one supporting means relatively to the other, and means for vibrating the pan in a rotary path.

50 10. In a screen separating means, the combination of screen supporting means adjustable to interchangeably support screen pans of different sizes, means adjustable to support the pan supporting means upon different 55 sizes and shapes of receptacles, connecting means comprising a pair of anti-friction bearings between said two supporting means whereby the pan may be vibrated with one supporting means relatively to the other, and means for vibrating the pan in a rotary path.

60 11. In a screen separating means, the combination of screen supporting means adjustable to interchangeably support screen pans of different sizes, means adjustable to support 65 the pan supporting means upon

different sizes and shapes of receptacles, connecting means comprising a pair of anti-friction bearings between said two supporting means whereby the pan may be vibrated with one supporting means relatively to the other, and means for vibrating the pan in a rotary path and comprising a motor driven eccentrically operated crank connected with the pan supporting means.

70 12. In a screen separating means, the combination of means adjustable to support a screen pan on tanks of varying shapes and sizes and comprising a supporting frame, pan supporting means within said frame and spaced laterally from said frame and adjustable to support pans of different sizes, a plurality of clamps slidably clamped to said frame for movement along the same and adapted to be clamped to the tank, and means for vibrating the pan in a rotary path.

75 13. In a screen separating means, the combination of a supporting frame having means for attaching it to different sizes and shapes of receptacles, supporting means within said frame and supported therein for rotary vibratory movement in a horizontal plane, adjustable to support screen pans of different sizes, a separating pan carried thereby, a motor support extending rearwardly thereof and carried by said frame, and means carried by said support and connected with said pan supporting means for imparting rotary vibratory movement to said pan relatively to said frame in a horizontal plane, the construction being such that the frame, pan supporting means, pan, motor support and pan operating means may be applied to or removed from a receptacle as a unit.

80 14. In a screen separating means, the combination of a supporting frame having means for attaching it to different sizes and shapes of receptacles, supporting means within said frame and supported therein for rotary vibratory movement in a horizontal plane, adjustable to support screen pans of different sizes, a separating pan carried thereby, a motor support extending rearwardly thereof and carried by said frame, and means carried by said support and connected with said pan supporting means for imparting rotary vibratory movement to said pan relatively to said frame in a horizontal plane, and comprising an eccentrically operated means consisting of a bevel gear comprising an eccentric hub, a crank connected therewith and with the pan supporting means, and motor driven means for operating said bevel gear, the construction being such that the frame, pan supporting means, pan, motor support and pan operating means may be applied to or removed from a receptacle as a unit.

85 Signed at Cleveland, Ohio, this 31st day of March, 1928.
